UNITED STATES PATENT OFFICE.

FRED EARL FISHERING, OF EUREKA, CALIFORNIA.

CUTTING MECHANISM FOR DISPLAY-RACKS.

1,191,777.

Specification of Letters Patent. Patented July 18, 1916.

Application filed August 23, 1915. Serial No. 46,996.

To all whom it may concern:

Be it known that I, FRED EARL FISHERING, a citizen of the United States, residing at Eureka, in the county of Humboldt and State of California, have invented certain new and useful Improvements in Cutting Mechanism for Display-Racks; and I do declare the following to be a full, clear, and exact description of the invention, such as

10 will enable others skilled in the art to which it appertains to make and use the same.

This invention relates to improvements in display racks and more particularly to racks for displaying oil cloth or other rolled 15 fabric.

The object of the invention is to so construct a rack of this character that various kinds of cloth may be displayed and one kind may be quickly, easily and accurately 20 measured and the required amount cut therefrom.

Another object of the invention is to provide a simple and efficient rack of this character equipped with improved clamping and 25 cutting means whereby the cloth may be held and cut when desired.

With these and other objects in view, the invention consists of certain novel features of construction, and the combination and 30 arrangement of parts as will be hereinafter more fully described and claimed.

In the accompanying drawings: Figure 1 represents a front elevation of a rack equipped with this improved cutting and 35 clamping mechanism with the clamping mechanism shown in operative position; Fig. 2 is an end elevation thereof; Fig. 3 is an enlarged detail end elevation showing the clamping member in open position; Fig. 4 is an enlarged detail front elevation with the clamping member shown in open position. Fig. 5 is a transverse vertical section taken on the line 5—5 of Fig. 1; Fig. 6 is an 40 enlarged detail top plan view with the clamping members shown closed; Fig. 7 is an enlarged detail front elevation of the knife and its mounting.

In the embodiment herein illustrated a rack is shown composed of two upright 45 standards 1 and 2 having laterally extending feet 3 at their lower ends and which are connected by cross bars 4, 5 and 6 suitably spaced apart, said bars being herein shown one arranged near the bottom of the rack and two adjacent the top thereof. The supporting feet 3 of this rack are herein shown

connected with the standards 1 and 2 by means of socket members 7 although obviously they may be connected in any other suitable or desired manner and these socket members are shown provided with laterally extending flanges 8 which are bolted to a head 9 which connects the feet 3. The bottom cross bar is also shown connected with the socket member 7.

Roll supporting brackets 10 are arranged on opposite sides of the standards 1 and 2 and are here shown in the form of upwardly curved arms having recesses 11 in their free ends for a purpose to be described. These brackets or arms 10 are here shown connected at their inner ends with a fastening plate 12, being preferably cast integral with said plate. These plates 12 are shown connected to the standards 1 and 2 by suitable 75 fastening elements, screws being preferably employed for this purpose. These bracket carrying plates are arranged on the standards 1 and 2 in longitudinally spaced relation, the brackets on one standard being arranged in alinement with those on the other to adapt them to receive and support rolls of fabric to be displayed and shown at R. Fabric supporting rods or bars 13 are shown detachably mounted in the sockets or recesses 11 formed in the free ends of the brackets 10 and project at their opposite ends beyond said brackets to form a reliable support for the fabric to be displayed, a portion of which is unrolled and passed over 80 these bars in the usual manner.

The upper ends of the standards 1 and 2 are connected by a shelf-like top or plate 14 which may be of any suitable or desired width, being here shown wider than the standards 1 and 2 and projecting at one edge beyond the flat faces of said standards so that the edge thereof overhangs and preferably extends slightly beyond the free ends of the arms or brackets 10 for a purpose to 100 be described. The projecting portions of these top plates 14 are here shown supported by angular brackets 15 connected with the lower face of the top 14 and the front faces of the standards 1 and 2 (see Fig. 2). This shelf-like top plate 14 is provided at its front edge on its upper face with a longitudinally extending rib 16 for a purpose to be described.

A clamping member 17 is hinged at its rear edge to the rear edge of the plate 14, said edges being shown beveled as at 18 to

adapt the member 17 to be opened and supported in upright position as shown in Fig. 3, the beveled ends abutting when said member is in this position and thus forming stops 5 for limiting its rearward movement, the bevel being so formed that the hinged member when raised extends slightly beyond the perpendicular being tilted slightly backward to prevent the possibility of its accidentally 10 dropping forward into closed position. This hinged clamping member is preferably cut away throughout the greater portion of its length from its rear edge to a point beyond the center thereof, said cut away portion 15 extending throughout its length a distance between the standards 1 and 2 corresponding in length to the width of the fabric which is to be carried by the rack and passed through this cut-away portion or opening 20 when it is desired to measure off and cut a portion from the roll of fabric. The lower face of this hinged clamping member is lined with felt or other suitable fabric 20 which is designed to frictionally engage and hold the 25 cloth clamped between said member and the stationary top 14 when it is desired to cut a portion from the roll. As shown a metal bar 21 overlaps the inner edge of the felt 20 and secures it to the top 17 by means of screws 22 30 which pass through said metal strip or bar and the felt over which it is placed and enter the material constituting the clamping member 17. This clamping member 17 is of a width slightly less than the distance between the inner edge of the rib 16 and the rear edge of the plate 14 so that when said member 17 is in closed clamping position a groove 23 will be formed between the front edge of the clamping member and the inner 35 face of the rib and thus provide a guide-way for the blade of the cutter which is carried by the hinged clamping member and will now be described.

This improved cutter is shown in the form 45 of a casting 24 which is slidably mounted on a rail 25 mounted on the outer face of the member 17 adjacent its free front edge, said rail being secured to said member in any suitable manner, screws being here shown 50 connected to said member and the rail being shown round in cross section although obviously it may be of any other desired cross sectional contour. The casting or block 24 has its front edge arranged flush with the 55 front edge of the member 17 when in applied position and a knife blade 26 is secured to said front edge of the block 24 being preferably adjustably mounted thereon by means of screws 27 and 28 one of which pivotally 60 connects the blade to the block and the other extends through a longitudinally disposed slot 29 formed in the blade, the screw 27 being in the form of a set screw to provide for the vertical adjustment of the blade relatively to the block. This blade 26 depends

below the inner face of the member 17 and the cutting edge thereof is designed to enter the groove formed between the rib 16 and the inner edge of the member 17 when said member is in closed position, said groove 70 forming a guide for the blade and when the block 24 is moved longitudinally on the rail 25 this blade will operate to sever the fabric which is clamped between the members 14 and 17 and which is mounted therein in a manner hereinafter to be described. A handle 30 is shown in the form of a knob connected with the upper face of the block 24 and which is designed for operating said block and slide it on the rail 25 for reciprocating the knife back and forth, and a stop 25' is positioned to prevent its sliding off the end of the rail. This improved rack or stand may be composed of any suitable material and be of any desired height, the usual 80 stand being about five feet eight inches high and about four feet wide to receive and support rolls of oil cloth R in such a way that the various kinds of oil cloth may be displayed, each roll being supported on a pair of the alined brackets 10 carried by the standards 1 and 2. When the rolls of cloth are disposed in the brackets the free ends thereof are pulled down a few inches sufficient to show the design thereon and are supported by the rods 13 and this constitutes the display feature of the rack. A steel tape measure 31 is secured at one end to the front edge of the shelf or top member 14 and depends therefrom in position ready for use 85 so that when it is desired to measure a certain quantity of cloth from any desired roll it may be easily and quickly accomplished by the use of this measure in a manner now to be described. In the operation of the device the salesman stands in front of the stand and selects the roll of cloth desired, then places it on the top bracket at the back of the stand throws back the hinged clamping member 17 and reaching through the cut out portion or opening 19 grasps the end of the cloth and pulls it through said opening until said end extends flush with the end of the tape 31. A pull is then exerted on both the 90 tape and the cloth until the desired quantity of cloth has been drawn through the opening 19 as indicated by the number of inches on the tape measure. The clamping member 17 is then lowered into clamping engagement with the member 14. To sever the cloth at the desired point the carrier or blade carrying block 24 is then moyed along the rail 25 with the blade 26 entering the groove 95 between the front edge of the clamping member and the inner face of the rib 16 and thereby cutting off the cloth which extends over said groove leaving a neat straight edge which is obviously square with the side of the cloth. After the desired quantity has 100 been severed the roll may be removed from 105

the upper brackets at the rear of the rack and inserted in its proper place.

From the above description it will be understood that when the clamping member

5 17 is lowered into engagement with the cloth the felt lining carried on its inner face will grip said cloth and firmly hold it against slipping during the cutting operation.

I claim as my invention:

10 1. The combination of a supporting structure, a stationary shelf member having a longitudinal rib at its front edge, a cloth clamping member hinged to the rear edge of said stationary member and of a width 15 slightly less than the width of said stationary member between said rib and its rear edge thereby providing a groove between said rib and the front edge of the hinge member when the latter is closed, a longitudinally disposed rail carried on the outer face 20 of said hinge member adjacent its free front edge, a carrier slidable on said rail and having a blade projecting over the edge of said member in position to enter said groove, 25 said clamping member being cut out longitudinally to form a passage for the material to be cut.

2. The combination of a supporting structure, a stationary shelf member having a longitudinal rib at its front edge, a cloth clamping member hinged to the rear edge of said stationary member and of a width 30 slightly less than the width of said stationary member between said rib and its rear edge, thereby providing a groove between said rib and the front edge of the hinge member when the latter is closed, a longitudinally disposed rail carried on the outer face 35 of said hinge member adjacent its free edge, a carrier slidable on said rail and having a blade projecting over the edge of said member in position to enter said groove, 40 said clamping member being cut out longitudinally to form a passage for the ma-

terial to be cut, and means carried by one 45 of said members for preventing slipping of the material to be cut when the clamping member is closed.

3. A clamping and cutting mechanism for fabric comprising a stationary plate having 50 a longitudinally extending rib on one edge thereof on its upper face, the other edge thereof being beveled, a clamping member hinged at its rear edge adjacent the beveled edge of said stationary member and having 55 said edge beveled to correspond with the bevel of said stationary member, a rail carried on the outer face of said hinged member adjacent its front edge, a block slidably mounted on said rail with its front edge arranged flush with the front edge of said member, and a cutting blade mounted on the front face of said block and extending 60 below the inner face of said hinged member.

4. The combination of fixed and movable 65 clamping members hingedly connected, the free edge of said fixed member projecting beyond the free edge of said movable member and having a cutter blade guide on its upper face adjacent to but spaced from the 70 free edge of said movable member when the latter is in closed position, a guide on the outer face of said movable member adjacent its free edge, a block slidably engaged with 75 said guide, a longitudinally slotted cutter blade longitudinally and laterally adjustable on the front face of said block, and positioned to extend over the free edge of said movable clamping member into the space between it and the guide of the fixed 80 member.

In testimony whereof I have hereunto set my hand in presence of two subscribing witnesses.

FRED EARL FISHERING.
